DESIGN FOR A FURNACE CASING

William Stuart Somers, Columbus, Ohio

Application November 4, 1937, Serial No. 72,624

Term of patent 14 years

To all whom it may concern:

Be it known that I, William S. Somers, a citizen of the United States, residing at Columbus, in the county of Franklin and State of Ohio, have invented a new, original, and ornamental Design for a Furnace Casing, of which the following is a specification, reference being had to the accompanying drawing, forming a part thereof.

Fig. 1 is a perspective view of the furnace casing showing my new design;

Fig. 2 is a top plan view thereof.

I claim:

The ornamental design for a furnace casing, as shown.

WILLIAM STUART SOMERS.
